(57) **CLAIM**

I claim the ornamental design for a display panel with graphical user interface, as shown and described.

DESCRIPTION

FIG. 1 is a front view of a first embodiment of a display panel with graphical user interface; and,

FIG. 2 is a front view of a second embodiment of a display panel with graphical user interface.

The long dashed broken line below the broken line text “--today” forms part of the claimed design. All other broken lines illustrate environment and form no part of the claimed design.

1 Claim, 2 Drawing Sheets

FIG. 1

FIG. 2
